UNITED STATES PATENT OFFICE.

HERBERT J. DALY AND WILLIAM L. TOBIAS, OF TORONTO, ONTARIO, CANADA.

SHOE-SHINING MACHINE.

1,264,279.

Specification of Letters Patent. Patented Apr. 30, 1918.

Application filed December 20, 1917. Serial No. 208,027.

To all whom it may concern:

Be it known that we, HERBERT J. DALY and WILLIAM L. TOBIAS, both subjects of the King of Great Britain, and residents of the 5 city of Toronto, county of York, Province of Ontario, in the Dominion of Canada, have invented certain new and useful Improvements in Shoe-Shining Machines, described in the following specification and illustrated 10 in the accompanying drawings, that form part of the same.

The principal objects of the invention are, to devise a neat and compact form of machine for automatically polishing shoes 15 which readily adapts itself to various shapes and sizes of shoes and effectively cleans and polishes the shoe in a manner similar to the method employed in hand polishing.

A further object is to provide a machine 20 which can be utilized in polishing both black and tan shoes.

A still further object is to devise an apparatus which allows of ease in placing and removing the shoe and is manipulated in a 25 simple manner.

The principal features of the invention consist in the novel construction and arrangement of parts, whereby polishing strips of fabric are operated with a back and 30 forth movement over the toe and around the side and heel portions of the shoe and whereby the polishing cloth is shifted to apply the polish and then to polish the surface to which the polishing material has been 35 applied.

In the drawings, Figure 1 is a plan view of the mechanism employed in carrying this invention into effect.

Fig. 2 is a side elevational view, parts of 40 the supporting frame being broken away.

Fig. 3 is a front elevational view.

Fig. 4 is a vertical sectional elevational view taken from the rear through the line 45 *a—b* of Fig. 1.

Fig. 5 is a perspective detail of a portion of the front end of the machine.

Fig. 6 is a perspective detail of the connecting member for transmitting the polishing action from the front or toe polishing 50 mechanism to the heel polishing members.

Fig. 5^a is a perspective detail of the means

for governing the action of the toe polish receptacles.

Fig. 7 is a perspective detail of the polish container and supporting arms. 55

Like numerals of reference indicate corresponding parts in each figure.

Referring to the drawings, 1 is the base of the machine having at the forward end an upwardly projecting portion 2 formed 60 with an inwardly and upwardly projecting web 3 carrying at the inner end the foot plate 4 upon which the shoe to be cleaned is placed. The plate 4 is located substantially in the center of the machine and above the 65 base.

5 is a pair of lugs extending upwardly from the base at the forward end and adjacent to the side.

6 is a frame having the upwardly extending arms 7 pivotally supported from the lugs 5 upon screw studs 8. 70

9 and 10 are lugs forming part of the frame 6 arranged at the front and rear ends thereof and at the outer sides. 75

11 are roller pins rotatably mounted in bearings in the lugs 9 and 10 having the bell crank arms 12 arranged on each end thereof, the long ends 13 of said arms extending inwardly toward the center of the machine. 80

14 are roller pins extending between the long ends of the pairs of bell crank arms 12.

15 is a connecting rod pivotally connected to the pins 16 arranged on the end of the short arms 17 of the front bell cranks 12, the 85 connecting rod extending across the front of the machine. The pairs of bell crank arms are so arranged that when the arms at one side are in a raised position the arms at the opposite side of the machine are in a lowered position, as shown particularly in Fig. 3.

18 is an electric motor supported upon a bracket 19 extending upwardly from the pivotal frame 6. 95

20 is a spur gear wheel rotatably mounted on the arm 21 extending inwardly from the bracket 19. The gear 20 meshes with a spur pinion 22 on the electric motor shaft and is driven thereby. 100

23 is a pitman having one end thereof journaled on a pin 24 on the inner side of

the spur gear 20 and at the outer end connected to a pin 25 arranged intermediate of the length of the connecting rod 15. The pitman 23 imparts a crosswise reciprocating motion to the connecting rod 15 which imparts a rocking motion to the bell crank arms 12, causing the inner ends carrying the roller pins to be swung downwardly and upwardly respectively alternately on either

10 side of the foot plate 4.

The frame 6 is of open construction and its under front and back portions are formed with transverse guideways 6' in which a rectangular shaped frame *a* is slidably arranged. A pair of drums *b* and *c* are journaled in the ends of the frame *a* and extend longitudinally thereof parallel to each other, the said drums each having spur gears *d* at one end adapted to intermesh so 20 that upon the rotation of one of the drums through external means the other drum will be rotated coincident therewith in an opposite direction.

The spindle of the drum *b* is provided 25 with a bevel pinion *e* at the forward end which is adapted to mesh with a bevel gear segment *f* secured upon a shaft 70 which will be more fully described hereafter. A dog *g* is spring held in engagement with the 30 gear pinion *e* to form a brake and the spur end *h* is engaged by the gear segment *f* as it moves into mesh with the pinion and thus releases the brake.

26 is a fabric belt having one end thereof 35 wound upon the drum *c* and extending outwardly under the adjacent roller pin 11 and it passes upwardly beneath the outer roller pin 14 and extending over the foot plate 4 it passes under the roller pin 14 of the bell 40 crank arms 12 at the opposite side and outwardly around the roller pin 11, the other terminal end being secured to the drum *b*.

The cloth extending over the foot plate is 45 adapted to engage the toe and vamp portions of the shoe when placed thereon. Upon the operation of the bell crank arms 12 in their alternate upward and downward motion the cloth is drawn over the toe of the shoe in a backward and forward movement.

50 27 are bell crank arms pivotally supported on the roller pins 11 preferably at the inner sides of the arms 12 and supporting at their outer ends the polish holding receptacles 30. These receptacles are here shown in the form 55 of a rectangular box open at one side and having a movable bottom 31 provided with pins 32 extending outwardly through slots 33 in the ends of the receptacle and pivotally supported in the long ends of the bell crank 60 arms 27.

The bell crank arms 27 are provided with 65 downwardly extending ends 28 and coil tension springs 29 are secured to these extension ends and to the frame 6 to hold the long ends of the arm 27 so as to maintain

the polish receptacles 30 in contact with the polishing belt.

The arms 28 are provided with laterally extending pins 28'.

i is a bar having longitudinal slots *j* at 70 each end thereof and the pins 28' on the arms 28 extend through said slots. The slots *j* are so arranged that when the polish receptacle at one side of the machine is free to follow the cloth operating arms 13 in their 75 upward and downward movement and the pin 28' is free to move longitudinally within the slot. The slot at the other end of the bar *i* will be in such a position that its innermost end will be in engagement with the pin 80 of the arm 28 at the opposite side of the machine to hold the lower end of said arm in an outward position and the end carrying the polish receptacle in an extreme 85 downward position to hold the polish receptacle out of contact with the polishing cloth.

The bar *i* is operated by means of a bell crank lever *k* which is pivotally supported at its angle upon the pin *l* in the base 1, 90 one end of said lever being provided with a pin *m* to engage the groove of a collar *n* secured upon the shaft 70. The shaft 70 is adapted to be shifted longitudinally and consequently the bell crank lever swings on 95 its pivot. The end of the lever *k* engages a fork *p* in the bar *i* and consequently shifts said bar to throw either one or other of the polish receptacles out of operating contact with the distributing belt.

The frame *a* is adapted to be shifted laterally in the frame 6 so as to change the position of the endless belt to move the portion of the belt containing the polish taken 105 from the receptacle into contact with the surface of the shoe and then to bring a clean part of the belt into engagement with the shoe to polish it. The means for effecting this change will be hereinafter more fully described. The polish receptacles are arranged one on each side of the machine, one being adapted to contain a black polish and the one on the other side a tan polish, the belt being so manipulated that the portion of the belt adapted to carry one polish will 110 not interfere with the one carrying the other.

The tilting frame 6 is adapted to be swung upwardly and forwardly upon its pivot on the lugs 5 to allow the ready insertion of 115 the shoe or its removal from the machine and in order to support the portion of the polishing belt extending between the inward ends of the operating arms 12 we provide a pair of arms 34 which are pivotally supported in journal lugs 35 formed on the pivotal frame. These arms are arranged one at each side of the center web 3 of the foot plate support and collars 36 are rigidly secured thereto and provided with extend- 120 125 130

ing lugs 37 which are adapted to engage the web 3 upon the upward swinging of the frame to spread the arms apart so as to pass the foot plate and to engage the cloth and lift it from the shoe.

38 are vertically arranged spindles supported on each side of the machine in the bracket extensions 39 of the frame.

40 are bell-crank arms supported on the spindles 38 at the top and bottom thereof, rollers 41 being arranged between the arms on the said spindles.

42 is a bar shown in detail in Fig. 6 extending across the machine and pivotally connected at the ends to the short ends 43 of the bell crank arms 40. The long ends 44 of said bell crank arms extend inwardly toward the foot plate and are so arranged that when the pair at one side project forwardly the pair at the opposite side project rearwardly.

45 are rollers perpendicularly disposed between the inner ends of the pairs of bell-crank arms 40.

46 are vertical spindles arranged in the frame toward the rear end having the rollers 47 mounted thereon.

48 is a fabric belt extending around the outer sides of the rollers 47 and around the outer sides of the rollers 41 and 45 and adapted to extend around the heel portion of the shoe.

49 is a horizontal slideway extending across the back end of the machine having a sliding block 50 operating therein.

51 is a spindle rigidly secured in one end of the block 50 and rising therefrom having a drum 52 journaled thereon.

53 is a spindle rotatably journaled in the block 50 and having a drum 54 rigidly secured thereto. Each of the drums is provided with a spur gear 55 at the top which intermesh so that upon the rotation of the drum 54 through the rotatable spindle the drum 52 will be rotated in the opposite direction.

The ends of the fabric belt 48 are wound upon the drums 52 and 54.

56 are pairs of bell crank arms supported upon the spindles 38 and extending substantially parallel with the long ends 44 of the bell crank arms 40 and carrying at their inner ends the polish receptacles 57 which are constructed similar to the receptacles 30.

55 The inner short ends 58 on the arms 56 are joined by a cross connecting bar 59, slots being provided in the said connecting bar to allow of a limited movement of the polish receptacle carrying arms. This cross bar is adapted upon being moved laterally in either direction to swing either one or the other of the polish receptacles out of contact with the polishing cloth.

60 are pairs of bell crank arms mounted upon the spindles 46 having rollers 61 adapt-

ed to engage the inner sides of the polishing belt between the spindles 38 and 46. The short arms 62 of the bell crank arms 60 extend angularly inward and springs 63 are connected to said short arms and to pins 64 secured to the crank arms 56. These springs hold the polish receptacles toward the cloth and swing the long ends of the arms 60 outwardly to adjust the slack in the polishing cloth according to the size of shoe placed in the machine.

65 are lugs rising upwardly from the base 1 and pivotally supporting an arched member 66, which arched member is provided with an upstanding centrally arranged lug 80 portion 67 adapted to engage the loop of the polishing cloth which passes around the heel of the shoe.

The inner ends 62 of the crank arms 60 engage the arched member 66 holding the same forwardly. The rocking motion of the front cloth operating arm is transmitted to the rear cloth through the cross connecting member 42 which is provided with a slotted quadrant shaped perpendicularly disposed arm 68, the slot of which is adapted to receive a pin 69 secured to the short end of one of the rearward bell crank arms 12. The quadrant shape provides for the operation of the rear portion irrespective of the angle at which the front polishing portion is tilted.

70 is a shaft extending longitudinally of the machine and journaled in suitable brackets formed on the base. This shaft is adapted to be partially rotated by means of a lever 71 secured to the rear end and said shaft is also adapted to be moved longitudinally in its bearings for a purpose as will hereinafter appear.

The arched member 66 is provided with a forwardly extending lug member 72 which extends inwardly over the shaft 70 and engages the cam 73 secured on said shaft, which cam on the rotation of the shaft is adapted to lift upwardly upon the lug 72 to tilt the arched member backwardly and to draw the cloth clear of the heel of the shoe.

74 is a cam member secured to the shaft 70 at the forward end of the machine and is adapted to engage the knob projection 75 extending forwardly from the tilting frame 6. The cam 74 is adapted to engage the knob 75 when the lever 71 is in a vertical position and to tilt the frame 6 to its uppermost raised position, holding the cloth clear for the insertion of the shoe and coincidentally the arched member 66 is tilted backwardly to hold the heel cloth clear.

When the shaft is rotated in either direction the front frame 6 is allowed to fall downwardly to bring the toe cloth over the shoe and the arched member 66 falls inwardly on the tension of the springs 63 to 130

bring the heel cloth into contact with the shoe.

76 is a lever pivotally mounted upon the base of the machine and extending rearwardly having a forked end 77 engaging a pin 78 secured in the block 50. The inner end of the lever 76 is provided with a short arm 79 which engages a cam groove 80 in a cam 81 mounted upon the shaft 70.

10 82 is a clutch operatively connecting the cam 81 with the shaft when said shaft is in the forward position.

When the lever 71 is turned to the left the cam 81 operates the lever 76 to slide the block 50 in the slideway 49, thereby drawing the cloth over the surface of the paste receptacle and bringing the moist portion into contact with the heel of the shoe. The front cloth is operated coincidently by 15 means of a cable 83 which is connected to the downwardly extending end 84 of the pin 78 secured in the block 50 and extends forwardly around the rollers 85 and 86 arranged on each side of the machine. The 20 ends of the cable are secured to the frame *a* carrying the drums *b* and *c* to which the forward cloth is secured, consequently on the transverse shifting of the block 50 the cable will move the forward cloth over the 25 roller pins 11 and carry the paste covered portion thereon over the toe portions of the shoe. The electric motor is then started automatically through contacts which will hereinafter be described and imparts a 30 reciprocating motion to both cloths through the mechanism described, applying the paste to the surface of the shoe.

When sufficient paste has been applied the 35 lever 71 is thrown over to the opposite horizontal position and through the cam 81 and lever 76 the block 50 is returned to its original position and the cable 83 coincidently returns the frame *a* to its original position. The paste covered portions of the cloth are 40 thus drawn clear of the shoe and the reciprocating action imparted by the motor then operates the cloths to polish the surface to which the paste has been applied.

Electric contacts are shown in dotted lines 45 in Fig. 3. These contacts are connected and arranged in such a manner that when the lever 71 is thrown to either horizontal position the electric circuit to the motor will be completed thus starting it into operation.

50 When it is desired to use a different kind of polish the lever 71 is pulled rearwardly and a gear segment 87 which is rigidly secured to the shaft is moved into mesh with a bevel pinion 88 secured upon the rotatable 55 spindle 53 carried in the block 50 and upon the rotation of the shaft 70 the drums 52 are rotated to shift the cloth so as to bring a different portion into contact with the shoe to apply paste from the desired paste receptacle.

Coincident with the movement of the gear segment 87 the cross bar 59 is shifted laterally by means of the bell crank lever 89 pivotally supported on the base and having a pin extending into a groove 90 in the 60 sleeve on the gear segment. The forward end 91 of the bell crank lever 89 is operatively connected with the cross bar 59 to effect a lateral movement. This lateral movement swings the polish receptacle, which has hitherto been out of engagement with the cloth, into engagement and correspondingly throws the other one clear.

The longitudinal movement of the shaft 70 moves the bevel gear segment *f* into mesh 65 with the pinion *e* on the toe cloth drum *b* and the turning of the shaft 70 rotates the drums *b* and *c* to shift the cloth and bring a different portion into contact with the shoe to apply paste from the desired paste receptacle, the paste receptacles being operated by the bell crank lever *k* as previously described.

When the gear segment 87 is out of mesh 70 with the pinion 88 the drums 52 are held 75 stationary by means of a spring latch 92 secured upon the downward extension of the pin 78 and likewise when the bevel pinion *f* is out of mesh with the pinion *e* the drums *b* and *c* are held stationary by 80 the spring dog *g*. Both these latches are adapted to be released by the operating gears when moved into mesh with the drum gears.

The operation of the machine is very simple and its flexibility is such that it instantly 85 adjusts itself to any size and shape of shoe and the looped portions of the cloths being operated with a back and forth movement similar to hand polishing imparts an excellent polish to the shoe.

90 It will be noted that the toe cloth is held to the shoe merely by the weight of the pivotal frame and the parts carried thereon consequently any accident to the operating mechanism will not prevent the removal of 95 the shoe from the machine.

This application is a substitute for our 100 original application Number 43,337 filed Aug. 2nd 1915 and contains the subject matter of the original application with additional matter required by the Patent Office in the prosecution of same.

105 What we claim as our invention is:—

1. A shoe polishing machine, comprising, 110 a frame, a shoe rest, a polishing belt adapted to engage the sides and heel of the shoe, a polishing belt adapted to extend over the toe portion of the shoe, means for imparting a back and forth movement to the portions of the belt contacting with the shoe, means 115 for applying polish to the belts, and means for shifting said belts to bring a different section thereof into engagement with the shoe to polish the same.

120 2. A shoe polishing machine, comprising, 125

a frame, a shoe rest, a polishing belt adapted to engage the sides and heel of the shoe, a polishing belt adapted to extend over the toe portion of the shoe, pivotally mounted 5 arms carrying rollers contacting with said cloths at each side of the shoe, and means for rocking the arms on one side of the shoe engaging said cloth in one direction and coincidentally rocking the corresponding arms 10 on the other side of the shoe in an opposite direction to cause the drawing of the cloth back and forth over the shoe surface.

3. A shoe polishing machine, comprising, a frame, a shoe rest, a polishing belt adapted 15 to engage the sides and heel of the shoe, a polishing belt adapted to extend over the toe portion of the shoe, pairs of bell crank arms arranged at each side of the toe and heel portions of the shoe, each pair having 20 rollers extending therebetween engaging the said cloths, and means connected to the free ends of the bell crank arms and imparting a rocking motion thereto, the arms on opposite sides of the shoe having motion in opposite directions.

4. A shoe polishing machine, comprising, a frame, a shoe rest, a polishing belt adapted to engage the sides and heel of the shoe, means for imparting a reciprocating motion 30 to said heel cloth, a frame pivotally mounted at the forward end of the machine and adapted to swing upwardly and forwardly, arms pivotally mounted on said pivotal frame arranged in pairs at each side 35 of the shoe and carrying rollers, a polishing belt extending around the rollers of said arms and over the shoe rest to engage the toe portion of the shoe, a connecting rod joining the pivotal arms on one side to the 40 pivotal arms on the other side, and means for imparting a reciprocating motion to said connecting rod.

5. A shoe polishing machine, comprising, a frame, a shoe rest, a polishing belt adapted 45 to engage the sides and heel of the shoe, means for imparting a reciprocating motion to said belt, a frame pivotally mounted at the forward end of the machine and adapted to swing upwardly and forwardly, a pair 50 of bell crank arms pivotally mounted on each side of said pivotal frame and having rollers extending therebetween at their inner and outer ends, an endless belt extending around the outer side of the inner rollers 55 and under the outer rollers and over the shoe rest and adapted to engage the toe portion of the shoe, a connecting rod connected to the outer ends of the bell crank levers and arranged so that the levers on opposite sides 60 swing in opposite directions, a pitman connected to said connecting rod, a crank wheel rotatably mounted on said pivotal frame, an electric motor carried on said pivotal frame and operating said crank wheel, and means 65 for transmitting the swinging motion of the

forward arms to the means for operating the heel cloth.

6. A shoe polishing machine, comprising, a frame, a shoe rest, a polishing belt adapted to engage the sides and heel of the shoe, a polishing belt adapted to extend over the toe portion of the shoe, pairs of bell crank arms arranged at each side of the toe and heel portions of the shoe, each pair having 70 rollers extending therebetween engaging said belts, a connecting rod joining the free ends of the forward bell crank arms and operating the arms on opposite sides of the shoe in opposite directions to draw the cloth over the toe of the shoe, a connecting rod joining the free ends of the rear bell crank arms and having a perpendicularly arranged guide-way therein and a pin projecting from the free end of one of the rearward arms of the forward set of arms and extending into 75 said guideway and adapted to impart a transverse reciprocatory motion to the connecting rod corresponding with the transverse motion of the forward connecting rod.

7. A shoe polishing machine, comprising, a frame, a shoe rest, a polishing belt adapted to engage the sides and heel of the shoe, rocking arms adapted to impart a reciprocating motion to the heel cloth, a connecting rod joining the rocking arms at each side of 90 the shoe and extending transversely of the machine and having at one side an arc-shaped slotted member, a frame pivotally mounted at the forward end of the machine, a polishing belt adapted to extend over the 95 toe portion of the shoe, rocking arms pivotally mounted in said pivotal frame and adapted to be swung upwardly and downwardly to draw the toe cloth back and forth over the shoe, a pin secured to one of said 100 forward rocking arms and extending into the slotted arc-shaped member of the rear connecting rod and adapted to impart thereto a transverse reciprocating motion, and means for rocking said forward arms. 110

8. A shoe polishing machine, comprising, a frame, a shoe rest, a polishing belt adapted to engage the sides and heel of the shoe, a polishing belt adapted to extend over the toe portion of the shoe, means for imparting 115 a back and forth movement to the portions of the belts engaging the shoe, arms pivotally mounted and supporting polish receptacles and adapted to hold the said receptacles in contact with the belt, and means 120 for shifting the position of the polishing belt in relation to the polish receptacle and shoe.

9. A shoe polishing machine, comprising, a frame, a shoe rest, a polishing belt adapted 125 to engage the sides and heel of the shoe, a polishing belt adapted to extend over the toe portion of the shoe, means for imparting a back and forth movement to the portions of the belts engaging the shoe, arms pivotally 130

- 6 mounted adjacent to the polishing belts, and receptacles loosely supported at the inner ends of said arms open at one side and having loose bottoms, said bottoms having pins 5 extending through slots in the ends of said receptacles and being pivotally secured to said arms and adapted to bring the paste into contact with the inner side of the polishing belt.
10. A shoe polishing machine, comprising, a frame, a shoe rest, a polishing belt adapted to engage the sides and heel of the shoe, means for imparting a reciprocating motion to said heel belt, a frame pivotally mounted 15 at the forward end of the machine and adapted to swing upwardly and forwardly, arms pivotally mounted on said pivotal frame arranged in pairs at each side of the shoe and carrying rollers, a polishing belt 20 extending around the rollers of said arms and over the shoe rest to engage the toe portion of the shoe, a connecting rod joining the pivotal arms on one side to the pivotal arms on the other side, means for imparting 25 a reciprocating motion to said connecting rod, and means for tilting said pivotal frame upwardly and forwardly to clear the toe of the shoe.
11. A shoe polishing machine, comprising, 30 a frame, a shoe rest, a frame pivotally mounted at the forward end of the machine and adapted to swing upwardly and forwardly, arms pivotally mounted on said pivotal frame arranged in pairs at each side of the shoe and carrying rollers, a polishing belt 35 extending around the rollers of said arms and over the shoe rest to engage the toe portion of the shoe, means for rocking said pivotal arms to operate the polishing belt, a cam projection formed on said pivotal frame, a shaft journaled in the frame of the machine, a cam arranged on said shaft and adapted to engage the cam on said frame to tilt said frame upwardly and forwardly to clear the shoe and to be swung 40 clear thereof to allow the belt to rest on the top of the shoe.
12. A shoe polishing machine, comprising, 45 a frame, a shoe rest, a frame pivotally mounted at the forward end of the machine and adapted to swing upwardly and forwardly, arms pivotally mounted on said pivotal frame arranged in pairs at each side of the shoe and carrying rollers, a polishing belt 50 extending around the rollers of said arms and over the shoe rest to engage the toe portion of the shoe, means for imparting a rocking motion to said arms, and means adapted to engage the underside of the loop of the 55 polishing belt to retain it in a raised position on the tilting of the frame and the withdrawal of the shoe.
13. A shoe polishing machine, comprising, 60 a frame having a rigid projection at the front end, a shoe rest, a frame pivotally 65 mounted at the forward end of the machine and adapted to swing upwardly and forwardly, arms pivotally mounted on said pivotal frame arranged in pairs at each side of the shoe and carrying rollers, a polishing belt 70 extending around the rollers of said arms and over the shoe rest to engage the toe portion of the shoe, means for imparting a rocking motion to said arms, a pair of pivotal arms journaled in bearings carried 75 on said pivotal frame and adapted to swing laterally to engage the loop of the polishing belt, said arms having inwardly projecting members adapted on the tilting of the frame to engage the rigid projection of the stationary frame and to swing said arms laterally to clear the foot plate.
14. A shoe polishing machine, comprising, a frame, a shoe rest, a polishing belt adapted to extend over the toe portion of the shoe, 80 means for imparting a back and forth movement to said belt, a polishing belt adapted to engage the sides and heel of the shoe, means for supporting said heel belt and reciprocating same in contact with the shoe, a member 85 slidably arranged in the frame and having the ends of the heel belt secured thereto, means for sliding said slidably member to effect the shifting of the heel belt, and means connected with said slidably member adapted 90 to shift the toe belt.
15. A shoe polishing machine, comprising, a frame, a shoe rest, a polishing belt adapted to engage the sides and heel of the shoe, means for supporting said heel belt and reciprocating same in contact with the shoe, a member 95 slidably arranged in the frame and having the ends of the heel belt secured thereto, a lever pivotally mounted in the frame and engaging said slidably member 100 and having a bell crank projection, a shaft rotatably supported in said frame, a cam arranged on said shaft and adapted to operate the bell crank end of said lever to shift the 105 slidably member.
16. A shoe polishing machine, comprising, a frame, a shoe rest, a polishing belt adapted to engage the sides and heel of the shoe, means for supporting said heel belt and reciprocating same in contact with the shoe, 110 a transverse slide-way arranged at the rear of said frame, a block slidably arranged in said slide-way, a fixed spindle secured to said block, a drum rotatably mounted on said spindle and secured to the heel belt, a rotatable spindle mounted in said block, a drum fixed to said rotatable spindle and secured to the other end of the heel belt and geared to said rotatable drum, a toothed pinion secured to said rotatable spindle, a shaft journaled slidably in the frame, and a gear segment secured to said shaft and adapted to 115 be moved into mesh with said gear pinion to rotate the drums and shift the position of the heel belt.
- 120
- 125
- 130

17. A shoe polishing machine, comprising a frame, a shoe rest, a polishing belt adapted to engage the sides and heel of the shoe, means for supporting said heel belt and reciprocating same in contact with the shoe, a member pivotally supported from the frame and engaging the loop of the heel belt, a shaft rotatably arranged in the frame, a cam arranged on said shaft adapted to operate said loop engaging member to withdraw the loop from contact with the heel of the shoe prior to removal of the shoe from the machine, and means for taking up the slack in the heel belt according to the size of 15 shoe.

18. A shoe polishing machine, comprising a frame, a shoe rest, a polishing belt adapted to engage the sides and heel of the shoe, means for supporting said heel belt 20 and reciprocating same in contact with the shoe, a transverse slide-way arranged at the rear of said frame, a block slidably arranged in said slide-way, a fixed spindle secured to said block, a drum rotatably mounted on 25 said spindle and secured to the heel belt, a rotatable spindle mounted in said block, a drum fixed to said rotatable spindle and secured to the other end of the heel belt and geared to said rotatable drum, a toothed pinion secured to said rotatable spindle, a shaft journaled slidably in the frame, a gear segment secured to said shaft and adapted to be moved into mesh with said gear pinion to rotate the drums and shift the position 30 of the heel belt, polish holding receptacles, pivotal arms supporting said polish receptacles adjacent to the belt one on either side and adapted to contain different kinds of polish, a connecting rod joining said pivotal 35 arms and holding either of said receptacles out of contact with the polishing belt when the other is in contact, a bell crank lever pivotally supported from the frame and having one end operatively connected with said 40 connecting rod and the other end having a pin extending into a groove in the hub of 45 said gear segment.

Copies of this patent may be obtained for five cents each, by addressing the "Commissioner of Patents, Washington, D. C."

19. A shoe polishing machine, comprising, a frame, a shoe rest, a polishing belt adapted to engage the sides and heel of the shoe, a 50 polishing belt adapted to extend over the toe portion of the shoe, means for imparting a back and forth movement to the portions of the belts engaging the shoe, means for shifting the rear belt to bring a different 55 section thereof into engagement with the shoe, and means connected with said shifting means and operatively connected with the toe belt and adapted to shift said toe belt coincidently with the shifting of the heel 60 belt.

20. A shoe polishing machine, comprising, a frame, a shoe rest, a polishing belt adapted to engage the sides and heel of the shoe, a 65 polishing belt adapted to extend over the toe portion of the shoe, means for imparting a back and forth movement to the belts engaging the shoe, means supporting polish receptacles arranged one at each side of the shoe adapted to be brought into contact with 70 said belts, means for operating said polish receptacle supporting means to coincidently move one set of receptacles into contact with the belts and to move the other set out of contact, and means for shifting the position 75 of the polishing belts in relation to the polish receptacles and shoe.

21. A shoe polishing machine, comprising, a frame, a shoe rest, a polishing belt adapted to engage the sides and heel of the shoe, a 80 polishing belt adapted to extend over the toe portion of the shoe, means for imparting a back and forth movement to the portions of the belts engaging the shoe, drums connected to the ends of said belts, means for 85 shifting the position of said drums to shift the belt to bring a different portion thereof into contact with the shoe, and means for rotating said drums to shift the belt to bring a still different portion thereof into contact 90 with the shoe.
